UNITED STATES PATENT OFFICE.

WILLIAM WESLEY KATTERHEINRICH, OF NEW KNOXVILLE, OHIO.

PLOW ATTACHMENT.

SPECIFICATION forming part of Letters Patent No. 689,194, dated December 17, 1901.

Application filed September 7, 1901. Serial No. 74,676. (No model.)

To all whom it may concern:

Be it known that I, WILLIAM WESLEY KATTERHEINRICH, a citizen of the United States, residing at New Knoxville, in the county of Auglaize and State of Ohio, have invented a new and useful Plow Attachment, of which the following is a specification.

This invention relates generally to plows, and more particularly to an improved construction of plow attachment whereby the ground turned by the plow is broken and smoothed and leveled.

The objects of the invention are to provide a device capable of performing these operations, and one which shall be exceedingly cheap, simple, and efficient, and one which can be applied to any of the plows now in use.

With these objects in view the invention consists in the peculiar construction of the various parts and in their novel combination or arrangement, all of which will be fully described hereinafter and pointed out in the claims.

In the drawings forming part of this specification, Figure 1 is a perspective view showing the practical application of my invention. Fig. 2 is a top plan view. Fig. 3 is a detail section on the line 3 3 of Fig. 2. Fig. 4 is a detail section on the line 4 4 of Fig. 2.

In carrying out my invention I employ a flat metal plate A, the forward end of which is curved upwardly, as shown at A'. A metal bar B is attached to the plate upon the upper side adjacent to the forward end, said bar extending upwardly, as shown at B', and horizontally, as shown at B², the end thereof having an opening B³, through which passes the eye C of the clip C', the said clip being secured to one of the handle members of the plow D.

E indicates a metal bar, which is attached also to the upper face of the plate A and extends diagonally from the rear end to a point adjacent to the forward end. The bar is then curved upwardly, as shown at E', and at its forward end is provided with an opening E², through which passes the eye C of the clip C', said clip being secured to the plow-beam at a point in advance of the handles. The bars E

and B are braced by means of brace-bars F and G, said bars F and G being connected to the bar E about midway its length by means of a bolt G', the rear ends of said bars F and G being connected to a horizontal portion B² of the arm B by means of bolts F' and F². A plate H, carrying a series of teeth H', is bolted to the upper face of the plate A, the teeth H' projecting through openings A² produced in the plate. The bolts H², which connect the plates A and H, extend upwardly through the plates and carry the nuts H³ upon their upper ends. The teeth H' project a considerable distance below the plate, thereby serving to break up the lumps of earth, the curved end of the plate serving to smooth down or level the earth prior to the action of the teeth.

By means of this attachment rough ground turned up by the plow can be quickly and easily broken and smoothed or leveled, and it will of course be understood that the attachment can be used upon either a right or left hand plow.

Having thus fully described my invention, what I claim as new, and desire to secure by Letters Patent, is—

1. A plow attachment comprising a plate, the forward end of which is curved upwardly, the bars rigidly attached to the said plate, clips to which the said bars are attached and a plate carrying a series of teeth, said plate being attached to the main plate, the teeth projecting through said main plate, substantially as described.

2. A plow attachment, comprising a plate, the forward end of which is curved upwardly, bars B and E rigidly attached to the said plate, said bars being braced by means of the bars F and G, the clips having eyes to which the ends of the bars B and E are connected and the plate H carrying teeth, said plate being adapted to be secured to the main plate, the teeth projecting through the said main plate, substantially as described.

WILLIAM WESLEY KATTERHEINRICH.
